APPARATUS FOR CUTTING SHEET MATERIAL

Filed Feb. 17, 1950

UNITED STATES PATENT OFFICE

2,552,674

APPARATUS FOR CUTTING SHEET MATERIAL

Urban C. Haren, Akron, Ohio, assignor to The B. F. Goodrich Company, New York, N. Y., a corporation of New York

Application February 17, 1950, Serial No. 144,637

6 Claims. (Cl. 164—39)

1

This invention relates to the trimming or otherwise cutting of sheet material to width and is especially useful in trimming sheet packing or flooring of vulcanized sheet rubber material as well as other sheet materials of plastics, compositions, textile fabrics or the like, to provide strips of uniform width.

In the manufacture of sheet material of rubber or other compositions for flooring or packing it is necessary to trim the material to uniform width. In such apparatus as has been proposed heretofore for accomplishing trimming of such sheet material as it is unwound from a roll and wound upon another, difficulty has been experienced in holding the material to uniform width due to the unstable manner of supporting the knives or material one or both of which have been objectionably deflected during the cutting operation.

It is an object of this invention to provide for even trimming or other cutting operations, to provide stable mountings for the cutters, to provide for clamping of the material by rolling pressure applied close to the cutter, to provide ease of adjustment for cutting different widths, and to provide for ready access of the cutting blades.

These and other objects will appear from the following description and the accompanying drawings.

Of the drawings,

Fig. 1 is a front elevation of apparatus constructed in accordance with and embodying the invention, parts being broken away.

Fig. 2 is an end elevation thereof.

Fig. 3 is a sectional enlarged detail view of the apparatus of Figs. 1 and 2.

Fig. 4 is a cross-sectional view taken on line 4—4 of Fig. 1.

Referring to the drawings which show an embodiment of the invention, the numeral 10 designates a base or support on which are mounted a pair of spaced apart roll-frame members 11, 12. These frame members are slotted vertically to receive roll bearings 13, 14, 15, 16. The roll bearings 13, 14 are seated at the bottoms of the slots and rotatably support a roll shaft 17. The bearings 15, 16 are slideably mounted in the slots for adjustment and rotatably support a roll shaft 18.

For adjusting the upper roll toward and from the lower roll, a cap-plate 19 is fixed to the tops of the roll frames. Adjusting screws 20, 21 are threaded to engage the threads of vertical openings in the cap-plate and their lower ends are rotatably secured to bearings 15, 16. Sprockets

2

22, 23 are fixed to the respective screws 20, 21 and are connected by a chain 24. A hand wheel 25 is fixed to screw 20. The arrangement is such that the bearings 16 may be raised and lowered in unison.

For supporting the sheet material 26, a roll 27 is fixed to shaft 17. A pressure roll 28 is fixed to shaft 18 to hold the sheet material against buckling during cutting thereof. Shafts 17 and 18 have gears 30, 31 and 32, 33 secured at their opposite ends and meshing with each other for moving the rolls in unison.

For driving the rolls, a sprocket 34 fixed to shaft 17 is driven from a convenient source of power, such as a motor (not shown) by means of a chain 35.

For cutting the sheet material a pair of parallel rails 36, 37 are secured at their ends to the roll-frames 11, 12 and extend parallel to the roll 28. Collars 40, 41 are slideably mounted on bars 36, 37 respectively and may be clamped thereto by screws 38, 39. A knife bar 43 is adjustably secured to collars 40, 41 by screws 44, 45 and supports a knife blade 46, such as a razor blade, clamped thereto by screws 47. A second knife bar 50 is supported in similar manner by similar collars 51 from rails 36, 37. As the knife bars are supported at their opposite ends from the rails 36, 37 the knife blades on the knife bars are rigidly supported against deflection and may be adjusted along the rails to any desired spacing.

For supporting the sheet material against buckling, the roll 28 is built of sections which may be adjusted and assembled as desired. These roll sections may be set close to the knife bars and provide annular spaces therebetween for clearing the knife blades and their clamping means. For this purpose, the roll 28 has two end sections 55, 56 each comprising a hub 57, a radial flange 58 and a rim band 59. The hubs have keyways for engaging keys 60 secured to the shaft and are secured by set screws 61, the hubs extending outwardly of the roll for access to their set screws. The rim band 59 overhangs the flanges 58 to provide annular clearance space for the knife blade 46 and its clamping means beyond which the face of the roll overhangs.

The center section of the roll comprises a series of hubbed pulleys 53, 54 distributed at spaced-apart intervals along the shaft and adjustably secured to the shaft by set screws. These pulleys support stave members 62, 63, 64, which are secured to the faces of the pulleys by screws 65. Staves of different lengths are sup-

plied in sets so that they may be assembled on the pulleys to provide supporting faces of different lengths between the knife blades. The staves 62 and 64 may be relatively short so that they may remain in place permanently while the staves 63 are removed and replaced by staves of different lengths when trimming different widths of material. The overhang of the pulleys permits adjustment of the roll face close to the lines of cut to support the material close to the cut.

The roll 27 is covered with rubber or other material as at 68 to support the sheet material to be cut and permits setting of the knives so as to cut entirely through the material, the covering of the roll protecting the knives from being dulled by contact with the metal roll.

The sheet material is delivered to the cutting mechanism from a supply thereof and under a guide roll 66 supported from frame members 11, 12 by brackets 61. After passing between rolls 27, 28 where the material is trimmed to width it is rewound on suitable rewinding mechanism (not shown).

The invention provides for supporting the trimming knives rigidly in the desired spaced-apart relation and permits holding and steadyng the material between the rolls at both sides of and close to each knife.

Variations may be made without departing from the scope of the invention as it is defined by the following claims.

I claim:

1. Apparatus for cutting sheet material, said apparatus comprising a pair of cooperating pressure rolls, means for driving the rolls, one of said rolls comprising axially spaced-apart roll sections adjustable axially of the roll, at least one of said roll sections comprising a pair of head members and removable staves connecting said head members, cutting knives independently supported between said roll sections for contact with the opposite roll at positions between the roll sections, and supports extending along the rolls at each side thereof for adjustably securing the knives.

2. Apparatus for cutting sheet material, said apparatus comprising a pair of cooperating pressure rolls, means for driving the rolls, one of said rolls comprising axially spaced-apart roll sections adjustable axially of the rolls, said sections having annular clearance pockets at their ends for clearing cutters, stationary cutters located in said pockets and supported by bars extending between said roll sections, and means for adjustably supporting said bars.

3. Apparatus for cutting sheet material, said apparatus comprising a pair of cooperating pressure rolls, means for driving said rolls, means for adjusting one of said rolls toward the other, one of said rolls comprising axially spaced-apart sections, said sections having inwardly spaced supporting heads and overhanging faces defining annular clearance pockets at their ends for clear-

ing cutters, stationary cutters located in said pockets and contacting the opposite roll through a space between said overhanging faces, bars extending between the roll sections for supporting said cutters, and means at each side of the rolls for adjustably supporting the ends of said bars.

4. Apparatus for cutting sheet material, said apparatus comprising a pair of cooperating pressure rolls, roll-driving means, one of said rolls comprising axially spaced-apart sections, a clearance pocket between said sections, supports at each side of the rolls, a bar secured to said supports and extending between the roll sections, and a cutting knife supported on said bar between the roll sections within said pocket and extending outwardly of the roll between said roll sections to engage material between said rolls.

5. Apparatus for cutting sheet material, said apparatus comprising a pair of cooperating pressure rolls, roll-driving means, one of said rolls comprising axially spaced-apart sections adjustable axially of the roll, said sections having clearance pockets at their ends for clearing cutters, supports at each side of the rolls, bars adjustably secured at opposite ends thereof to said supports and extending between ends of the roll sections, and cutting knives supported on said bars within said clearance pockets and extending outwardly of the roll between said roll sections to engage material between said rolls.

6. Apparatus for cutting sheet material, said apparatus comprising a pair of cooperating pressure rolls, means for driving said rolls, one of said rolls comprising axially spaced-apart sections adjustable axially of the roll, said sections having roll faces overhanging their opposed ends in closely spaced relation for supporting material close to a cutter, supports for cutters extending parallel to the rolls at each side thereof, a bar adjustably secured at opposite ends thereof to said supports, and extending through the space between said roll sections, and a cutter secured to said bar between said sections interiorly of the overhanging faces and extending outwardly thereof toward the face of the opposite roll.
